DIGESTER

Augustus C. Durdin, Jr., Chicago, Ill.

Application October 19, 1938, Serial No. 235,744

8 Claims. (Cl. 210—2)

This invention relates to digesters and particularly to digesters in which the decomposition of sewage, sludge and other organic materials is conducted under anaerobic conditions.

Organic decomposition of this type is accompanied by the evolution of gas of considerable calorific value. This gas is normally burned for useful purposes and usually at least some of the heat derived therefrom is utilized for the heating of the material being decomposed, since the decomposition is considerably accelerated by reasonably high temperature, of the order of 90° or 100° F.

One of the principal objects of the invention is to provide an improved digester which not only serves to decompose the sludge, but also advantageously serves for the storage of a substantial amount of gas.

According to the present invention I prefer to use the body of the digester as a receptacle for a gas collecting dome. In order to attain this result in a satisfactory manner I have found it necessary to protect the interior of the dome from floating solid material derived from the sludge. Such floating material for some reason or other tends to agglomerate at the surface of the liquid and to coalesce on the apparatus at that level. I have found that it does not so coalesce if kept submerged or if kept in motion. As will hereinafter be described, the surface upon which such solid materials may float is reduced to relatively small proportions and such floating solid material is effectively kept in motion by diverting the gas produced through said surface, or the material is kept submerged by means which permit the escape of gas upwardly.

The general objects, advantages and capabilities of the invention will readily be understood from the following description of three preferred embodiments thereof, taken in conjunction with the accompanying drawings, in which:

Figure 1 is a vertical section through a digester embodying the invention;

Fig. 2 is a similar view through a modified digester embodying the invention, and

Fig. 3 is a similar view through a modified digester embodying the invention.

Referring to Fig. 1, my digester comprises a basin 10 which may suitably be built of concrete. This basin may be round, square, or of other suitable shape in cross-section. It is preferably relatively deep and is provided with a hopper bottom 11. From its lowermost point extends an outlet pipe 12 controlled by a suitable valve (not shown) so that the mud-like precipitate result-

ing from the decomposition may be drawn off at will.

Within the tank 10 is a heating coil 13 through which circulates any suitable medium heated by the combustion of some or all of the gas produced by the digester, in well known manner. The tank 10 is provided with an inlet pipe 14 for the introduction of fresh sludge, this inlet being controlled by a suitable valve (not shown). The reference numeral 15 designates a pipe for withdrawal of the gas produced. This pipe extends through the wall of the basin 10 at a low position thereof to a point approximately at the center of the basin, whence it extends upwardly to a point substantially at the upper level of the basin.

The vertical portion of the pipe 15 is supported by a standard 16. It will, of course, be understood that the pipe 15 is controlled by a suitable valve or valves (not shown). For the withdrawal of the clear supernatant liquor I provide a plurality of pipes 17 which extend through the wall of the basin 10 and terminate within the basin at various levels. The exterior portion of each pipe 17 extends upwardly to an overflow trough 18. This trough is adapted to overflow into a channel 19 and is arranged so that it may receive liquid which overflows from the basin 10. Adjustable weirs 20 and 21 may be provided to control the level at which overflow may occur. The outer end of each of the pipes 17 is closed by means of a valve 22 which can be opened manually to withdraw supernatant liquor at the draw-off level of any of the pipes 17.

At the suitable position within the lower part of the basin 10 I provide a circumferential series of brackets 23 which project for a short distance radially into the basin. These brackets serve as a support for a housing 24. This housing comprises a substantially cylindrical wall 25, a roof 40 or cover 26 which is preferably domed upwardly toward its center. At its center the roof 26 is provided with a relatively small cylindrical outlet member 27 which extends upwardly above the normal liquid level defined by the weir 21. The vertical length of the pipe 15 extends upwardly over the outlet 27, as seen in Fig. 1.

The housing 24 is slightly smaller than the basin 10 so as to provide a free annular space 28 in which the cylindrical skirt 29 of a gas dome 30 may move freely in accordance with variation of the amount of gas within the dome. It will be noted, as shown in Fig. 1, that when the gas is withdrawn, the dome 30 moves downwardly and in its lowest position it is supported by the brackets 23.

It will be understood that the digester is operated in usual manner, sludge to be digested being introduced periodically by the pipe 14 and digested residue being withdrawn periodically by the pipe 12. The digesting sludge is maintained at a suitable temperature by means of the heating coil 13. During digestion a considerable amount of gas is produced. This gas moves upwardly into contact with the sloping roof 26 which directs it to the gas outlet 27. The gas passes upwardly through this outlet into the dome 30. As the gas collects, the dome 30 floats in the liquid in the basin. Gas is withdrawn by the pipe 15 when required. Clear supernatant liquid is withdrawn by the pipes 17. Any solid material which tends to float moves upwardly into contact with the cover 26, which prevents it from moving to the surface. Consequently, the solid materials are prevented from encrusting on the apparatus and they eventually sink, after being deprived of the gas which buoys them upward. A certain amount of solid materials extend into the gas outlet 27, but they are maintained in continuous movement by the gas escaping upwardly through this outlet and, consequently, they do not become encrusted on the surface of the outlet, but become deprived of their gas and sink.

In the embodiment of the invention shown in Fig. 2, similar parts have been given similar reference numerals. In this embodiment the brackets 23 are omitted and the basin 10 is provided with an inwardly extending shoulder 31 which serves as a continuous support for a flange 32 provided around the lower edge of the housing 24.

This housing is firmly anchored to the ledge 31 by means of suitable bolts 33. The ledge 31 also serves as a support for a gas dome 30 when the same is in its lower position, as shown in Fig. 2. This gas dome operates in the annular space 28 between the housing 25 and the wall of the basin 10. It is to be noted that this annular space, and if desired also the annular space above the cover 26, contains sealing water. These spaces are out of communication with the space within and below the housing 25 so that initially water has to be provided for the sealing of the gas dome. Ordinarily this water does not need to be replaced since a certain amount of condensation normally occurs on the inner side of the dome and the condensate may pass through an overflow 34 into a run-off trough 35.

The pipes 17 are shown diagrammatically as being controlled by valves 36, which valves may be located at any desired position.

It will readily be understood that the digestion process conducted in this apparatus is substantially similar to that described in connection with the embodiment of Fig. 1.

The embodiment of the invention shown in Fig. 3 is largely similar to that shown in Fig. 2 and, consequently, similar reference numerals are applied to corresponding elements. In this embodiment of the invention the inverted bell or cover 26 comprises an annular wall 37 which is secured to the ledge 31 by bolts 33. The upper wall 38 of the inverted bell 26 is perforated so as to permit gases to escape upwardly into the bell 26. The perforations in the wall 38 are sufficiently small to keep solids of any substantial size submerged in the liquid. Since the wall 38 is capable of passing gases, the gas outlet 27

of the previously described embodiments is omitted. The gas discharge pipe 15 passes through an opening in the center of the wall 38.

The perforate or foraminous wall 38 may suitably consist of a woven screen of appropriate mesh to prevent any but the smallest solids from passing through. Thus, I may employ a wire screen of $\frac{1}{8}$ " mesh or finer, such as $\frac{1}{12}$ " or $\frac{1}{16}$ " mesh, or a screen of even finer mesh. In some cases, however, I prefer to employ a grille or screen having a larger opening size or mesh.

The operation of this embodiment of the invention is substantially similar to that of the previously described embodiments. In this embodiment, however, the solids of any substantial size are maintained submerged by the foraminous wall 38. Gases pass freely through this wall in the upward direction. Solids tending to float which are stopped by the screen 38 become degassed and gravitate to the bottom of the digester. It will be noted that the fall of the liquid level resulting from the periodic withdrawals of sludge causes a downward flow of clear liquid through the screen 38 so that any material which tends to collect on the screen is washed away at frequent intervals and the screen is maintained clear.

Although the invention has been disclosed in connection with the specific details of preferred embodiments thereof, it must be understood that such details are not intended to be limitative of the invention except in so far as set forth in the accompanying claims.

Having thus described my invention, what I claim as new and desire to secure by Letters Patent of the United States is:

1. A digester comprising a tank, means defining a normal liquid level therein, a wall extending transversely of said tank, means maintaining said wall at a fixed position below said normal liquid level whereby it is normally submerged in said liquid, a gas collecting inverted bell adapted to be gas floated in said tank, said inverted bell having a skirt extending downwardly into the liquid space between the first said wall and the wall of the tank, said transverse wall having perforations therein to permit upward passage of gas while preventing large solids from moving upwardly into contact with the interior of said bell, means for supplying material to said tank, means for withdrawing material from said tank, and means for withdrawing gas from said inverted bell above said liquid level.

2. A digester comprising a tank, means defining a normal liquid level therein, a drum, means maintaining said drum normally submerged within said tank below said liquid level, the side wall of the drum being in spaced relation to said tank, a gas collecting inverted bell adapted to be gas floated in said tank around the said drum, the upper end of said drum being of screen material to permit upward passage of gas while preventing large solids from moving upwardly into contact with said gas collecting inverted bell, means for supplying material to said tank, means for withdrawing material from said tank, and means for withdrawing gas from said gas collecting inverted bell above said liquid level.

3. A digester comprising a tank, means defining a normal liquid level therein, an impervious wall extending transversely of said tank, means maintaining said wall normally submerged at a fixed position below said level, said wall terminating short of the tank wall, a gas outlet extending upwardly from first said wall to a posi-

tion above said level, a gas collecting inverted bell adapted to be gas floated in said tank, said inverted bell having a skirt extending downwardly into the liquid space between the first said wall and the wall of the tank, means for supplying material to said tank, means for withdrawing material from said tank, and means for withdrawing gas from said inverted bell above said liquid level.

4. A digester comprising a tank, means defining a maximum liquid level therein, an inverted bell, means maintaining said bell in a fixed position and normally submerged within said tank below said liquid level and located in spaced relation to the wall of said tank, said bell having a gas outlet extending upwardly to a position above said liquid level, a gas collecting inverted bell adapted to be gas floated in said tank, last said bell having a skirt extending downwardly into the liquid space between the first said bell and the wall of the tank, means for supplying material to said tank, means for withdrawing material from said tank, and means for withdrawing gas from said gas collecting inverted bell above said liquid level.

5. A digester comprising a tank, means defining a maximum liquid level therein, supporting means at an intermediate height in said tank, an inverted bell supported in said tank by said supporting means in a position below said liquid level, said bell extending into close propinquity and in spaced relation to the wall of the tank, said bell having a gas outlet extending upwardly to a position above said liquid level, an inverted gas collecting bell adapted to be gas floated in said tank, said collecting bell having a skirt extending downwardly into the space between first said bell and the wall of the tank, means for supplying material to said tank, means for withdrawing material from said tank, and means for withdrawing gas from said gas collecting inverted bell above said liquid level.

6. A digester comprising a tank, means defining a maximum liquid level therein, an inverted bell supported in said tank in a position below said liquid level, said bell extending into close and spaced relation to the wall of the tank, means supporting said bell and establishing liquid-tight

relation with the wall of the tank to provide an annular space around said bell adapted to contain liquid separated from the liquid in the main portion of the tank, said bell having a gas outlet extending upwardly to a position above said liquid level, a gas collecting inverted bell adapted to be gas floated in liquid in said annular space, means for supplying material to said tank, means for withdrawing material from said tank, and means for withdrawing gas from said gas collecting inverted bell above said liquid level.

7. A digester comprising a tank, means defining a maximum liquid level therein, the wall of the tank being provided with a ledge at a position below said liquid level, an inverted bell within said tank in a position below said liquid level, said bell being supported upon and being sealed to said ledge and being arranged in close and spaced relation to the wall of the tank above said ledge, said bell having a gas outlet extending upwardly to a position above said liquid level, a gas collecting bell adapted to be gas floated in liquid in the annular space between the first said bell and the tank wall, last said bell being supported by said wall in its lowest position, means for supplying material to said tank, means for withdrawing material from said tank, and means for withdrawing gas from said gas collecting inverted bell above said liquid level.

8. A digester comprising a tank, means defining a maximum liquid level therein, an open drum supported in said tank in a position below said liquid level, said drum extending into close and spaced relation to the wall of the tank, means supporting said drum and establishing liquid-tight relation with said wall of the tank to provide an annular space around said drum, screen material enclosing the upper wall of said drum whereby solid materials are maintained submerged, while gas is permitted to pass upwardly, a gas collecting inverted bell adapted to be gas floated in said annular space, means for supplying material to said tank, means for withdrawing material from said tank, and means for withdrawing gas from said inverted bell above said liquid level.

AUGUSTUS C. DURDIN, JR.
